UNITED STATES PATENT OFFICE.

DAVID B. CARSE, OF SHARON, CONNECTICUT, ASSIGNOR TO SUPERIOR SIGN COMPANY, OF NEW YORK, N. Y., A CORPORATION OF DELAWARE.

ILLUMINATED SIGN.

1,316,476.

Specification of Letters Patent. Patented Sept. 16, 1919.

Application filed May 16, 1918. Serial No. 234,931.

To all whom it may concern:

Be it known that I, DAVID B. CARSE, a citizen of the United States, residing at Sharon, in the county of Litchfield and 5 State of Connecticut, have invented certain new and useful Improvements in Illuminated Signs, of which the following is a specification.

My invention relates to improvements in 10 illuminated signs or similar devices, and has for its purpose to provide, by means of variously illuminated surfaces, a simulation or imitation of a moving body or object. I obtain the desired effect by interposing between a source of light and suitably arranged or designed surfaces, a movable or revolving screen or shade, variously colored on a prearranged scheme or plan whereby to transmit the light rays through 20 such moving screen in different successive color values, to present the appearance of any suitable subject.

In the drawings, which show the invention as applied to a sign representing an 25 automobile wheel,

Figure 1 is a face view of the apparatus in elevation;

Fig. 2 is a vertical section on the line II, II of Fig. 1;

30 Fig. 3 is a view of the rotatable lamp shade in elevation;

Fig. 4 is a diagrammatic development of the same, showing the arrangement of light transmitting color portions or zones;

35 Fig. 5 is a similar view showing a modification;

Fig. 6 shows a further modification.

The sign may be either single or double face, as indicated in Fig. 2, and comprises 40 a general base 2 comprising a front face portion, preferably concaved as shown toward the centrally arranged source of light, as lamp 3. The lamp is preferably of the nitrogen or concentrated filament type, 45 whereby the light rays are emitted from a central point toward the end of the lamp, which is a useful factor in connection with the distribution of the rays through the color value transmitting zone and stripes of 50 the rotatable shade 4.

When utilized as a wheel sign, to represent the revolving wheel of an automobile or the like, the outer portion of base 2 is provided with a circular rounded reflecting tire 55 member 5 and an inner concentric rim mem-

ber 6, each being preferably somewhat convexed toward the lamp for good reflecting effect and somewhat realistically presenting the appearance of an actual wheel. The lamp 3 is set in a central socket 7 extending 60 from the center of base 2, and upon the socket 7 or other suitable concentric mounting is journaled the rotatable shade holder 8 adapted to fixedly engage the inner end of shade 4.

Holder 8 is rotated at the desired speed by any suitable means, as a pinion 9 on shaft 10 actuated by suitable gearing 11—12 and engaging the teeth of an internal gear 13 of the shade holder.

Holder 8 is of glass, circular in form, preferably tapering inwardly toward its base as shown, and provided with an outer terminal in the form of nut 14 of hexagon or other form. This portion of the shade is 75 preferably colored yellow to present the appearance of a brass nut, in contrast to the other portions of the device, centrally of the hub.

The body of the shade is colored in a 80 contrasting color, as red, in the form of an encircling band *a* and longitudinal stripes *b* with intervening white or non-colored spaces *c*. The outer portion of the shade is likewise uncolored, or white, as at *d*, for its 85 full circumference. The outer rim face of the shade is also preferably colored red, as at *e*, presenting a red color hub appearance surrounding the yellow nut 14.

By this arrangement, when the shade is 90 rotated, continuous white rays will pass through the band *d* and will be reflected by the annular tire surface 5 and similar continuous red rays will pass through band *a* and will be reflected by the annular rim surface 6. The longitudinal red bands *b* and intervening uncolored bands *c* will, however, transmit corresponding narrow radiating bands of red light, simulating spokes, with intervening or alternating wide 100 radiating bands of white light, simulating the spaces between the spokes. The annular red portion *e* which is practically co-extensive with the diameter of holder 8 will correspond to the hub of the wheel, and the 105 exterior of the holder may also be colored red, to enhance the effect.

The general appearance of the entire device constitutes a close imitation of an actual revolving wheel, the spokes being 110

clearly and sharply defined against the surface of base 2, which may be painted white, as is also the tire surface 5.

For the purpose of more definitely imparting the appearance of rotation to the tire portion of the base, the annular clear portion *d* of the shade may be interrupted at intervals by opaque portions *f* as in the diagram, Fig. 5.

10 These will give the appearance of a moving tire somewhat more realistically than the entire clear space *d*, especially as assisted by the spoke imitation.

If preferred, the lamp itself may be rotatably mounted at the center of the wheel and be provided with the same general arrangement of colored and clear areas as indicated in Fig. 6, to give the same effect, the parts being indicated by similar numerals primed.

Other imitations may be made of various articles or objects within the taste or judgment of the designer, while the invention may also be changed or varied in different details, arrangement, or value of the colored glass shade, or in the proportioning of the various parts, but all such changes are to be considered as within the scope of the following claims.

30 What I claim is:

1. In combination, a stationary reflecting member having pre-arranged continuously annular form-defining portions in imitation of an entire physical object, and a centrally arranged lamp having a surrounding rotatable variously colored shade adapted to transmit emphasizing rays to said annular portions only and provided with a central terminal translucent ray transmitting portion formed in physical imitation of a co-acting element.

2. In combination with a circular reflecting base having an outer annular reflecting portion, a centrally arranged lamp having a surrounding rotatable glass shade provided with alternating colored and uncolored portions and an outer terminal portion of a contrasting color shaped in imitation of a hub nut.

45 3. In combination with a circular reflecting base having outer annular reflecting tire and rim portions, a centrally arranged

lamp having a surrounding rotatable glass shade provided with an annular clear portion for transmitting white light to the tire portion, an annular colored portion for transmitting colored light to the rim portion and a series of longitudinal alternating colored and clear portions for transmitting corresponding colored and clear light to the interior face of the base.

4. In combination with a circular reflecting base having outer annular reflecting tire and rim portions, a centrally arranged lamp having a surrounding rotatable glass shade provided with an annular clear portion for transmitting white light to the tire portion, an annular colored portion for transmitting colored light to the rim portion, a series of longitudinal alternating colored and clear portions for transmitting corresponding colored and clear light to the interior face of the base, and an outermost terminal portion in unit shape of a contrasting color.

5. In combination with a circular reflecting base having outer annular reflecting tire and rim portions, a centrally arranged lamp having a surrounding rotatable glass shade provided with an annular clear portion for transmitting white light to the tire portion, an annular colored portion for transmitting colored light to the rim portion, a series of longitudinal alternating colored and clear portions for transmitting corresponding colored and clear light to the interior face of the base, and an outermost terminal portion in unit shape of a contrasting color with an adjacent annular colored portion.

6. In combination with a circular reflecting base having outer annular reflecting tire and rim portions, a centrally arranged lamp having a surrounding rotatable glass shade provided with an annular clear portion interrupted by occasional opaque spaces for transmitting interrupted white light to the tire portion, an annular colored portion for transmitting colored light to the rim portion, and a series of longitudinal alternating colored and clear portions for transmitting corresponding colored and clear light to the interior face of the base.

In testimony whereof I hereunto affix my signature.

DAVID B. CARSE.
